UNITED STATES PATENT OFFICE.

HENRY KLECKLER, OF BUFFALO, NEW YORK, ASSIGNOR TO CURTISS AEROPLANE AND MOTOR CORPORATION, A CORPORATION OF NEW YORK.

FAN-PUMP.

1,283,529.

Specification of Letters Patent.

Patented Nov. 5, 1918.

Application filed November 17, 1916. Serial No. 131,964.

To all whom it may concern:

Be it known that I, HENRY KLECKLER, a citizen of the United States, residing at Buffalo, in the county of Erie and State of 5 New York, have invented certain new and useful Improvements in Fan-Pumps, of which the following is a specification.

My invention relates to aircraft and has reference more particularly to equipment 10 therefor consisting of an improved wind driven feed pumping system.

In the aeronautical art, and especially in hydroaeroplanes and flying boats, it is customary to locate the motor or propelling 15 power plant without and in a horizontal plane above the hull or body of the machine. The fuel supplied to the motor is fed by gravity from an elevated gravity feed tank seated thereabove preferably intermediate 20 the superposed supporting surfaces or planes. Another and much larger tank is located interiorly of the hull. From the latter, a storage tank, the fuel is pumped during flight continuously or uninterrupt- 25 edly into the gravity feed tank. It is to the latter end, *i. e.*—the pumping feature, that the present invention is designed.

The pumping unit, in its preferred embodiment, may be generally described as 30 comprising a housing, a pumping element, and a fan or pump driving means. The housing in its entirety is located and fastened interiorly of the fuel storage tank with its bottom end in engagement with the 35 tank bottom and its top end in engagement with the tank top. Being liquid-tight, the housing affords an inclosure for the pumping unit which at one end is extended thereinto. The opposite end of the pumping 40 unit is extended well beyond the deck of the hull for exposure at a point in the direct path of air rush during flight. It is at this end of the pumping unit that the fan or pump driving means is mounted. A partition, removable with the pump, subdivides 45 the housing horizontally into non-communicating compartments, the lower compartment affording an operating space for the pump proper and the upper compartment an 50 accessible inclosure of a size permitting repair, if necessary, of the inclosed pump parts. Openings are formed at the bottom end of the housing. Should occasion demand, the pumping unit in its ensemble may 55 be removed and replaced without soiling or

wetting the hands. An outlet or lead extends from the pump proper to the gravity feed tank. Such is the system of my invention.

In describing my invention in detail, reference will be had to the accompanying drawings wherein like numerals of reference designate like or corresponding parts throughout the several views, of which:

Figure 1 is a side elevation of a hydro-aeroplane (partly broken away) equipped with a pumping system or plant in accordance herewith;

Fig. 2 is a longitudinal sectional view of the pumping unit and its associated means;

Fig. 3 is a similar view in which the section is taken at right angles to that of Fig. 2;

Fig. 4 is a transverse section at the bottom of the pumping unit, and

Fig. 5 is a detail longitudinal sectional view of the pump proper and that portion of the pumping unit directly adjacent thereto.

In the embodiment of my invention selected for illustration, 10 designates the hull or body of a Curtiss flying boat. Supporting surfaces 11 including a built-in engine section panel, fin excrescences 12, and a rearwardly facing step 13, characterize the hull. Other characteristics such as the fin 85 braces 14, wing posts 15 and engine section panel braces 16 have been disclosed. Preferably the rearwardly facing step 13 is formed in the hull bottom in the vicinity of a vertical line projected through the center 90 of gravity.

Such a construction and arrangement of parts as I have already disclosed is only preferred and may be modified considerably without departing from the spirit of the invention as claimed.

Fuel storage tanks, three in number, designated respectively 17, 18 and 19, are located interiorly of the hull symmetrically as regards the center of gravity. Preferably all 100 variable load is thus located. The tanks 17 and 19 are slightly elevated with respect to the tank 18 to permit of gravity feed thereto. This arrangement will necessitate the employment of but a single pumping unit 105 and yet permit of fore and aft tank adjustment should such adjustment become necessary in balancing the machine.

The motor or propelling power plant (not shown) as stated, is located without the hull 110

- and in a horizontal plane thereabove intermediate the supporting surfaces. The engine section panel wing posts may thus jointly function as motor bed supports. The 5 gravity feed tank 20 is also located without the hull, the plane of the gravity feed tank being above that of the motor. Leads (not shown) extend from the gravity feed tank to the motor.
- 10 Since the gravity feed tank is located above the fuel storage tanks and since the motor is fed directly from the gravity feed tank, it is evident that a means must be installed whereby the stored fuel contained in 15 the storage tanks is transferred, while the machine is in flight to the gravity feed tank. This I accomplish by the pumping plant or system designated in its entirety by the numeral 21.
- 20 In its preferred embodiment, the pumping unit may be generally described as comprising a housing 22, open ended, cylindrical and of a length to engage at one end in a sump 23 formed at the bottom of the tank 18 25 and at its opposite end engage with the tank top. An opening 24 somewhat larger than the housing 22 is formed in the bottom of the tank 18 so that the housing, in assembling, may be passed therethrough. After securing 30 of the housing, the sump 23 is fitted over the opening in the tank. An annular outwardly directed flange 25 is formed at the bottom of the housing to engage in the sump and afford, in assembling, a centering 35 means therefor. If desired, the sump and housing may be made rigid by suitable fastening means arranged to penetrate both the flange and the sump. Fuel inlet openings 25' are formed in the housing at its lower 40 end.
- At its opposite end, the housing 22 is similarly flanged as indicated at 26, the flange contacting with the end surface of the tank top circumferentially of an opening 27 45 formed therein. Fastening devices 28 penetrate the flange 26, the tank top, and a washer 29 to secure the housing in place.
- Directly over the housing 22 an opening 30 is formed in the deck of the hull. 10 Through this opening, the pumping unit extends without the hull. At a point interiorly of the housing 22 adjacent the sump 23, the pumping unit terminates. Gears 31 and 32 constitute the pump proper. The 15 gear 31 is provided with a stud 33, polygonal in cross section, the stud engaging in a complementary socket 34 formed in an enlargement of a shaft 35 vertically disposed. Said shaft 35 comprises separable shaft sections designated respectively 36 and 37. The 20 shaft section 36 contacts directly the stud 33 and with the connected shaft section 37 affords a driving means for the pump gear 31. The gears 31 and 32 are in mesh.
- 25 The shaft 35 at its extended terminal is equipped with the pump driving means designated as an entirety by the numeral 38. This means may be generally described as comprising a fan 39, a fan shaft 40, and a bevel pinion 41. The said shaft 40 is mounted to extend forwardly beyond and without an appropriate two-part gear case 42, the terminals of the gear case affording bearings for said shaft. From the pinion 41, motion is transmitted to the vertical shaft 35 70 through the medium of a bevel gear 43 mounted on said shaft. Both the gear 43 and the pinion 41 are inclosed within the gear case. The sections 36 and 37 which constitute the shaft 35 are jointed together by 75 means of a sleeve 44 fastened at one end as indicated at 45 to the shaft section 37 and shaped at its opposite end to receive in its bore a polygonal head 46 formed on the shaft section 36. This construction will permit the pumping unit, excluding the pump proper and its directly associated means to be withdrawn from the housing 22 if desired.
- Removal of the pumping unit in its entirety is made possible by the peculiar mounting of the pump driving means 38 at the extended terminal of the shaft 35. Uprights 46' fastened as indicated at 47 to a cover plate 48 support the pump driving 80 means in its elevated or extended position. The cover plate 48 is preferably of a size and shape substantially complementary to the annular flange 26 of the housing to which it is indirectly fastened by any suitable means. 85
- The shaft 35, interiorly of the housing, is inclosed in a tube 49 extended at one end through the cover plate and at its opposite end into a recess formed by an upstanding flange 50 integral with a partition 51 located 90 interiorly of the housing and adjacent its bottom end. Beneath the partition 51 the gear case 52 for the pump gears 31 and 32 is located, the gear casing including in addition to a removable cover plate 53 an appropriate screening element 54 of a construction designed for arrangement beneath the cover plate to filter the fuel before its admission through the pump inlet opening 55 to the interior of the pump. Bolts 56 100 pass transversely through the partition 51, the pump casing and the pump casing cover 53. The bolts 56 also serve as the fastening means for the screen 54. When it is desired that the pump case cover plate be removed 105 without removing the pumping unit in its entirety, access is gained to the bolts 56 by first emptying the tank and thereafter removing the sump 23. A removable threaded plug 57 is located at the bottom of the sump 110 for draining the tank.
- The tube 49 at its opposite end is fastened by any suitable means to an upstanding flange 58 brazed to or integral with the cover plate for the housing. At its opposite end, 115
- 120
- 125
- 130

the tube is fastened as indicated at 59 to the upstanding flange 50. Through such an arrangement the cover plate 48 acts as the sole support for the entire pumping unit and the 5 pump driving means.

The pump outlet is located at the opposite side of the pump casing from that in which the inlet opening 55 is formed and designated 10 60. As indicated in Fig. 4, a lead 61 extends from the outlet opening 60 vertically 15 interiorly of the housing to and through the cover plate 48 where it is coupled as indicated at 62 to a flexible lead 63 discharging into the gravity feed tank 20.

15 Immediately the aircraft is set in motion, the air rush incident to flight will drive the fan 39. From the fan 39, through the intermediaries 40, 41, 43 and 35, motion is transmitted to the pump proper, *i. e.*,—the 20 gears 31 and 32. The suction created by the rotating gears will draw the liquid fuel into the housing 22 below the partition 51 through the openings 25', through the screen 54, the inlet opening 55 to the interior of the pump 25 casing where it is forced or pumped out through the opening 60 and via the leads 61 and 63 to the gravity feed tank 20. From the feed tank the fuel gravitates continuously and uninterruptedly to the motor or 30 35 motors. Fuel is thus supplied to the gravity feed tank at all times while the craft is in flight and the motor in operation.

To preclude the admission of extraneous matter to the interior of the housing at the 35 top end of the tube 49, a conical cover 64 rotatable with the shaft 35 is provided. The basal diameter of the cover is of such dimension as to extend beyond the upstanding flange 58 to which the tube is secured and 40 flush with which the tube terminates at its upper end. The partition 51 transversely divides the housing 22 into non-communicating compartments, the upper or larger compartment being liquid-tight and of an 45 interior size permitting access thereto without wetting or soiling the hands and without disengaging or disassembling any of the pump parts. To remove the pumping unit in its entirety it is but necessary that the 50 cover plate 48 be unfastened and bodily lifted with its various associated elements through the opening 30 in the hull of the craft. As stated, the cover plate 48 affords the sole support for the uprights 46, the 55 pump driving means 38 and the pumping unit. By reason of the flexible connections indicated at 63, the lead 61 is removable with the pumping unit. Wherever practical, the parts may be lightened and if extended 60 without the body of the hull, streamlined.

While in the foregoing there has been illustrated in the drawings and described in the specification such combination and arrangement of elements as constitute the preferred construction or embodiment of the 65

invention, it is nevertheless desired to emphasize the fact that interpretation of the invention should only be conclusive when made in the light of the subjoined claims.

What is claimed is:

1. In an aircraft, the combination of a fuel storage tank located interiorly of the body of the craft, a gravity feed tank located thereabove, and a propelling power plant, of a fuel pumping system including a pumping unit located interiorly of the fuel storage tank, an air driven pump driving means located exteriorly of the body of the craft in the direct line of air rush incident to flight, and a conduit leading from the 75 storage tank to the gravity feed tank for supplying fuel thereto uninterruptedly during operation of the pump driving means.

2. In an aircraft, the combination with a fuel storage tank located interiorly of the body of the craft, a gravity feed tank located without the body of the craft, and a propelling power plant, of a fuel pumping system including a pumping unit of a construction designed to extend at one end into the fuel storage tank and at its opposite end without the body of the craft, an air driven pump driving means mounted at the outer extended terminal of said pumping unit and in the direct line of air rush incident to 80 flight, and a conduit leading from the storage tank to the gravity feed tank for supplying fuel thereto uninterruptedly during 85 operation of the pump driving means.

3. In an aircraft, the combination with a fuel storage tank located interiorly of the body of the craft, a gravity feed tank located thereabove, and a propelling power plant, of a fuel pumping system including a pumping unit of a construction designed 100 to extend at one end into the interior of the fuel storage tank and at its opposite end without the body of the craft through an opening formed therein, an air driven pump driving means mounted at the outer 105 extended terminal of the pumping unit and in the direct line of air rush incident to flight, and a conduit leading from the storage tank to the gravity feed tank for supplying fuel thereto uninterruptedly during 110 operation of the pump driving means.

4. In an aircraft, the combination with a fuel storage tank located interiorly of the body of the craft, a fuel supply chamber, and a propelling power plant, of a fuel pumping system including the pumping unit located interiorly of the fuel storage tank, an air driven pump driving means located exteriorly of the body of the craft in the direct line of air rush incident to flight, and a conduit leading from the storage tank to the supply chamber for supplying fuel thereto uninterruptedly during 120 operation of the pump driving means.

5. In a fuel pumping system, the combi- 130

- nation with a fuel storage tank having a bottom sump formed therein, of a housing having fuel inlet openings formed therein for disposition at the sump, a pumping unit constructed to operate interiorly of said housing and to extend therethrough beyond the top thereof, associated exteriorly located air driven pump driving means, and a fuel outlet leading from the pump.
10. 6. In an aircraft fuel pumping system, the combination with the fuel storage tank, of a housing having fuel inlet openings formed therein, a pumping unit constructed to operate interiorly of said housing adjacent said openings and to extend at one end therewithout, a partition separating that portion of the housing having the inlet openings formed therein from the remainder thereof, associated exteriorly located driving means, and a fuel outlet leading from the pump.
7. In an aircraft fuel pumping system, the combination with a fuel storage tank, of a housing liquid-tight except for fuel inlet openings formed therein at the bottom end, said housing being submerged into the fuel tank and having the lower part thereof flooded with fuel passing through said openings, a pumping unit constructed to operate interiorly of said housing adjacent said openings and to extend at one end exteriorly thereof, a means maintaining the pumping unit fixed with respect to said housing, exteriorly located pump-driving means, and a fuel outlet pipe leading from the pump.
8. In an aircraft fuel pumping system, the combination with a fuel storage tank, of a housing liquid-tight except for fuel inlet openings formed therein, a pumping unit constructed to operate interiorly of said housing and to extend at one end considerably therewithout, a means dually functioning to partition the housing and preclude displacement of the pumping unit, pump driving means mounted at the outer extended terminal of said pumping unit, and a fuel outlet pipe leading from the pump.
9. In an aircraft fuel pumping system, the combination with a fuel storage tank, of a housing liquid-tight except for fuel inlet openings formed therein, pumping means operable within said housing adjacent said openings and of a construction designed to extend therethrough and beyond the top thereof, said pumping means being removable from the housing as a unit, driving means for the pump located without the housing, and a fuel outlet pipe leading from the pump.
60. 10. In an aircraft fuel pumping system, the combination with a fuel storage tank, of a housing liquid-tight except for fuel inlet openings formed therein at its bottom end, a bodily removable pumping unit of a construction designed to operate interiorly of
- said housing adjacent said openings and to extend at its opposite end without the housing, and air driven pump-driving means mounted at the extended terminal of the pumping unit.
11. In an aircraft fuel pumping system, the combination with a fuel storage tank, of an open ended housing liquid-tight except for fuel openings formed therein at its bottom end, a bodily removable pumping unit of a construction designed to operate interiorly of said housing adjacent said openings and to extend at its opposite end therewithout, pump-driving means mounted at the extended terminal of the pump unit, a cover plate for the housing removable with the pumping unit, and a fuel outlet pipe leading from the pump.
12. In an aircraft fuel pumping system, the combination with a fuel storage tank, of an open ended housing liquid-tight except for fuel openings formed therein at its bottom end, the housing at said bottom end directly contacting with the bottom of the tank, a cover plate for the opposite end of the housing adapted for securing to the tank, a pumping unit constructed to operate interiorly of the housing adjacent said openings and to extend at its opposite end through the cover plate, and pump driving means mounted at the extended terminal of the pumping unit, the cover plate and the driving means being removable with the pumping unit in disassembling the pump.
13. In an aircraft fuel pumping system, the combination with the fuel storage tank, of a housing having openings formed therein at its bottom end, a cover plate for the housing, a pumping unit constructed to operate interiorly of said housing adjacent said opening and to extend therewithout through the cover plate, pump driving means mounted at the extended terminal of the pumping unit, a support for the driving means mounted on the cover plate, a partition for separating that portion of the pumping unit adjacent said openings from the remainder thereof, and a fuel outlet pipe leading from the pump, the said outlet pipe, partition, driving means, support, and cover plate being removable as a unit with the pumping means in disassembling the pump.
14. In an aircraft fuel pumping system, the combination with a fuel storage tank having a sump formed in the bottom thereof, an open ended housing mounted interiorly of the tank to engage at one end with the tank bottom at the sump and at its opposite end to register with an opening formed in the tank top, a pumping unit constructed to operate interiorly of the housing adjacent said opening and to extend therewithout through the open top, a pump-driving means mounted at the extended termi-

nal of the pumping unit, a cover plate for the housing, and a support for the pump-driving means mounted on said cover plate.

15. In an aircraft fuel pumping system, 5 the combination with a fuel storage tank, of a housing designed for securement interiorly of the tank, a pumping unit constructed to operate interiorly of said housing and to extend therewithout, a pump- 10 driving means mounted at the extended terminal of the pumping unit, and a screening element removable with the pump.

16. In an aircraft fuel pumping system, 15 the combination of a fuel storage tank, located interiorly of the body of the craft, a propelling power plant, and a fuel pumping unit comprising a rigidly connected pump and wind driven driving fan therefor, the pump of which is projected within the tank 20 and connected with a propelling power plant, and the wind driven fan thereof projects without the body of the craft in a position to be acted upon by the air rush incident to flight.

25 17. In an aircraft fuel pumping system, a fuel storage tank located interiorly of the body of the craft, a gravity feed tank located without and in a horizontal plane above the body of the craft, a fuel pump lo-

cated interiorly of the storage tank, and 30 driving means direct-connected with said storage tank and including a fan located without the body of the craft in the line of air rush incident to flight.

18. A storage tank for liquid fuel comprising 35 a storage compartment, a housing for a pump inclosed in the storage compartment and submerged into the fuel contained therein, and a partition subdividing the housing into non-communicating compartments, one of which non-communicating compartments is provided with fuel inlet 40 openings for admitting fuel thereinto from the storage compartment.

19. In an apparatus of the type set forth, 45 a fuel storage tank comprising a storage compartment, a pump housing adapted to be inserted and submerged into the fuel contained in said storage compartment, said housing being provided with means for 50 flooding the lower portion thereof, a pump located in said flooded portion of the pump housing, and means arranged exteriorly of the storage compartment for driving said pump.

55 In testimony whereof I affix my signature.

HENRY KLECKLER.
